[57] **CLAIM**

The ornamental design for a hanger bracket for supporting sign boards or the like, substantially as shown and described.

DESCRIPTION

FIG. 1 is a front elevational view of a hanger bracket for supporting sign boards or the like showing my new design.

FIG. 2 is a view of one side of said hanger bracket for supporting sign boards or the like; the other side being a mirror image of same.

FIG. 3 is a rear view of the hanger bracket for supporting sign boards or the like depicted in FIGS. 1 and 2.

FIG. 4 is a top view of same.

FIG. 4

FIG. 1

FIG. 2

FIG. 3
